EXTENSION DEVICE

Filed Nov. 7, 1928

UNITED STATES PATENT OFFICE

EDWIN G. CARLSON, OF RIVERSIDE, RHODE ISLAND, ASSIGNOR TO SPEIDEL CHAIN CO., A FIRM COMPOSED OF FREDERIC SPEIDEL AND EUGEN SPEIDEL, BOTH OF PFORZHEIM, GERMANY, DOING BUSINESS IN PROVIDENCE, RHODE ISLAND

EXTENSION DEVICE

Application filed November 7, 1928. Serial No. 317,739.

This invention relates to a foldable extension device for enlarging the encircling length of a wrist band; and has for its object to provide a construction by which the 5 foldable sections will be securely held against unfolding.

A further object of the invention is the provision of the cover section which is pivoted so that it will swing at right angles to the swing of the foldable sections and better hold the sections against an unfolding movement.

A still further object of the invention is the provision of adjustment for the 15 circling size of the strap at each end of the side sections, which sections are of a combined length less than the body section so as not to overlap one another when in folded position.

With these and other objects in view, the invention consists of certain novel features of construction, as will be more fully described, and particularly pointed out in the appended 20 claims.

In the accompanying drawings:

Fig. 1 is a top plan view of the strap of my extension device in folded position.

Fig. 2 is a bottom view of the extension device in the same position as Fig. 1.

Fig. 3 is a view similar to Fig. 1 looking at the top of the strap with the cover swung to open position.

Fig. 4 is a top plan view with the sections in unfolded position.

Fig. 5 is a section on line 5—5 of Fig. 1.

Fig. 6 is a section on line 6—6 of Fig. 1.

Fig. 7 is a perspective view of the extension device detached from the straps and in open position.

It is found in the practical use of extension devices that they may under oppositely directed strains unfold or unclasp to the annoyance of the wearer; and in order to avoid this undesirable feature, I have provided a 40 cover which swings at an angle to the swinging of the foldable sections to better resist such unfolding strains; and at the same time

I have provided a pair of end sections which swing toward each other to substantially 45 abutting relation and carry with them the

strap to which they are attached to hide a large portion of the extension device from view when worn and by this construction the body of the extension device may be made of a relatively long arc shaped strip of metal and yet not be unsightly when in working position as the cover for holding these sections in folded position, which may be of comparatively small size, and may present the desired surface for ornamentation, is the 55 only part visible; and the following is a 60 detailed description of the present embodiment of this invention showing the preferred means by which these advantageous 65 results may be accomplished:

With reference to the drawings, 10 designates one strap part and 11 the other strap part which parts are connected together by an extension device 13 comprising a body section 14 generally rectangular in shape 70 with end sections 15 and 16 hinged thereto as at 17 and 18 to fold toward each other into the substantially abutting relation illustrated in Fig. 3. Each of these end sections is provided with flanges or side walls 75 19 having a series of holes 20 in its opposite side walls to receive an attaching pin in any selected position of adjustment for securing the tips 21 on the ends of the strap sections 10 or 11 thereto, it being understood that 80 where different sizes of adjustment are desired the pin will be placed in different sets of openings, and the adjustment may be made from either or both of the ends as desired.

In order to secure the end sections in folded position, such as is illustrated in Fig. 3, I have provided a cover 23 hinged as at 24 to the side of the body section 14, the hinge 24 being arranged at right angles to the hinges 17 and 18 so that the swinging movement of the cover 23 is at right angles to the swinging movement of the sections 15 and 16. In order that the proper relation of the parts may be provided, the body section is built out as at 25 to allow the cover to swing clear of the sections which it covers.

This cover is generally channel shaped with a flange 26 along one side provided with a recess 27 which may be snapped into engage- 10

ment with the rib 28 formed on an outstanding sheet metal wall 29 bent up from the other side of the body section 14 to releasably secure the cover in closed position. There is sufficient resiliency between the wall 29 and the flange or side wall 26 of the cover to permit of a firm clasping relation of these two parts so that lengthways strains upon the strap will not serve to swing the end sections on the body section or cause an opening 10 of the cover from its closed position.

By arranging the cover to swing at right angles to the end sections, the endways strains on the straps to swing them to open position 15 are better resisted and a more symmetrical unfolding of the parts is provided whereby the watch may be more easily positioned in the desired place on the wrist as may be required.

20 The foregoing description is directed solely towards the construction illustrated, but I desire it to be understood that I reserve the privilege of resorting to all the mechanical changes to which the device is susceptible, 25 the invention being defined and limited only by the terms of the appended claims.

I claim:

1. An extension device for a wrist strap, comprising a body section and an end section 30 hinged to each end of said body section to fold thereover toward each other, each end section having opposed flanges at the free end thereof, means extending between said flanges for securing a strap end thereto, the 35 combined length of said end sections being no greater than the length of the body section whereby the end sections do not overlap, and means for securing said sections in folded position.

40 2. An extension device for a wrist strap comprising a plurality of sections hinged together to be folded one over the other or unfolded to extended position, the end sections having strap end attaching means at the free 45 ends thereof, and a cover hinged to one of said sections to swing at right angles to the swinging of said sections and over said sections to hold them in folded position.

50 3. An extension device for a wrist strap comprising a body section, an end section hinged to each end of said body section to fold thereover, and having strap end securing means at the free ends thereof, and a cover carried by said body section and hinged 55 to swing at right angles to said end sections and over said end sections to hold them in folded position.

60 4. An extension device for a wrist strap comprising a body section, an end section hinged to each end of said body section to fold thereover toward each other, and having strap end securing means at the free ends thereof, the combined length of said two end 65 sections being no greater than the length of said body section whereby the end sections

do not overlap, and a cover carried by said body section and hinged to swing at right angles to said end sections and over said end sections to hold them in folded position.

5. An extension device for a wrist strap 70 comprising a body section, an end section hinged to each end of said body section to fold thereover, and having strap end securing means at the free ends thereof, a cover carried by said body section and hinged to swing at right angles to said end sections and over said end sections to hold them in folded position, a flange on said cover and cooperating means between said flange and body sections to hold said cover in closed position. 75

6. An extension device for a wrist strap comprising a body section, an end section hinged to each end of said body section to fold thereover, side walls on each end section, means to adjustably secure the strap between 80 said side walls, and means for securing said sections in folded position. 85

7. An extension device for a wrist strap comprising a body section, an end section hinged to each end of said body section to fold thereover, opposite side walls on each end section having a series of openings therein and a pin in each of said sections to selectively engage said opening to adjustably secure the strap ends thereto, and means for 90 securing said sections in folded position. 95

8. An extension device for a wrist strap comprising a body section, an end section hinged to each end of the body section, said end sections folding together on the same 100 side of the body section, side walls on each end section, means to adjustably secure strap ends between said side walls, and means for securing said sections in folded position.

In testimony whereof I affix my signature. 105
EDWIN G. CARLSON.
